UNITED STATES PATENT OFFICE.

ONEALL WATSON, OF CRAWFORDSVILLE, INDIANA, ASSIGNOR OF ONE-HALF TO WILLIAM A. FOWLER, OF SAME PLACE.

BOX-OPENING HATCHET.

SPECIFICATION forming part of Letters Patent No. 481,199, dated July 1, 1890.

Application filed May 24, 1889. Serial No. 311,990. (No model.)

To all whom it may concern:

Be it known that I, ONEALL WATSON, a citizen of the United States, residing at Crawfordsville, in the county of Montgomery and State of Indiana, have invented a new and useful Box-Opening Hatchet, of which the following is a specification.

This invention has relation to a combination-tool especially adapted for use in opening boxes and crates; and among the objects in view are to provide a cheap and convenient hand-tool for the purpose above described so constructed as to obviate the necessity of forcible blows, so arranged as to provide a powerful leverage, and which is adapted for use as a cutting-tool or hammer, and a nail-claw so arranged as not to require a change from one hand to the other, that will not mar the boards, and one in which the handle, besides its other functions, will serve the purpose of a screw-driver.

The invention consists in certain features of construction hereinafter specified, and particularly pointed out in the claims.

Referring to the drawings, Figures 1 and 2 are perspectives of a tool constructed in accordance with my invention, the same being shown in operative position. Fig. 3 is an enlarged perspective of the head. Fig. 4 is a transverse section of the same, the section being taken through the blade.

Like numerals of reference indicate like parts in all the figures of the drawings.

The head consists of a central thickened body portion 1, which is provided with an eye 2 for the reception of a suitable handle 3. At one side of the handle-eye 2 the head is reduced to form a diagonally-arranged cutting-blade 4, said blade being arranged at an angle to the plane of the head, and therefore also to the handle 3 and its eye 2, and crossing the longitudinal axis of the latter between the ends of the same.

The opposite end of the head 1 is projected beyond the opening 2 to form a reduced cylindrical hammer end 5, said end being more than of ordinary length and adapted to serve as a supplemental handle or hand-grip for a purpose hereinafter apparent. Upon the up-

per face of the head 1 and projecting slightly 50 above the same, and in a lateral relative direction, is formed a nail-claw 6, the rear end of which embraces the opening 2 formed in the head.

Upon the under surface of the head 1, and formed integral with the said head and encircling the opening 2, is a collar 7, one side of which is projected beyond the surface or side of the head, as at 8, to form a fulcrum, said fulcrum occurring at that side of the head opposite, upon which is located the claw 6.

The handle 3 terminates in a screw-driving end 9, and when in use the head serves as the handle, and by reason of its peculiar construction may be easily and conveniently grasped, the inclined blade 4 passing between the thumb and forefinger and the third and fourth and small finger encircling the hammer portion 5, the palm of the hand resting 70 upon the head or claw, whereby an efficient bearing-surface is provided.

The manner of handling the herein-described tool in the opening of boxes is as follows: By grasping the hammer portion with 75 the right hand and the handle 3 with the left and placing the cutting-edge against the crevice or opening intermediate the boards and pressing firmly with the right hand on the hammer part and working at the same time 80 the handle proper, the edge or blade 4 will be gradually inserted within the slightest opening. Then, by holding in place the head through the medium of the right hand and prying down upon the handle, the projection 85 8 upon the collar 7 acts as a convenient fulcrum, the outer side as a purchase, and the handle as a lever, and in this manner the board may be raised; and, by reason of the width of the blade 4, opposite edges of two 90 boards may be simultaneously started and raised, and this without splitting the same. After the first board is raised, hold the handle perpendicular, the cutting-edge down and from you, drop the hatchet-blade entirely 95 under the end of the lid at the left side, and place the small projecting fulcrum on side of box and pull back on the handle, which again

acts as a lever. When lids are slightly raised or started, strike the board sharply near the nail ends with the hammer end 5, which causes the nail-head to rise sufficiently to be 5 caught by the claw and removed. If desired, in lieu of the metal handle described, an ordinary wooden handle may be employed.

Having described my invention and its operation, what I claim is—

10 1. The herein-described tool-head, having a central handle-receiving eye and comprising at one side of its eye a blade, at the opposite side a hammer, and intermediate the two at one side a claw, and opposite the claw a ful-
15 crum projecting therefrom, substantially as specified.

2. The herein-described tool-head, comprising a central thickened body portion, perforated to receive a handle, and at its lower sur-
20 face and at one side provided with a later-
ally-projecting fulcrum, and upon its upper surface at its upper opposite lateral side with a nail-claw, and at one longitudinal side with a diagonally-disposed blade, and at its oppo-
25 site side with a hammer adapted to serve as

a supplemental handle for the blade, sub-
stantially as specified.

3. The herein-described combination-tool, consisting of the head 1, having the laterally-
opposite claw 6, collar 7, and lug 8, and the 30 intermediate eye 2, having the handle 3, ter-
minating in the screw-driver 9, and the blade
4, arranged at an obtuse angle to the handle
and at one longitudinal side thereof, and the
extended hammer portion 5 at the opposite 35 longitudinal side, substantially as specified.

4. The tool-head provided with a handle-
receiving eye, and terminating at one end in
a blade the cutting-edge of which is disposed
at an angle to and crosses the longitudinal 40
axis of the eye between the ends of said eye,
substantially as specified.

In testimony that I claim the foregoing as
my own I have hereto affixed my signature
in presence of two witnesses.

ONEALL WATSON.
